UNITED STATES PATENT OFFICE

152,895

DESIGN FOR A CHAIR

John Jacob Lubberts and Lambert James Mulder,
Grand Rapids, Mich., assignors to Tomlinson
of High Point, High Point, N. C., a corporation
of North Carolina

Application November 12, 1946, Serial No. 134,687

Term of patent 14 years

(Cl. D15—1)

To all whom it may concern:

Be it known that we, John Jacob Lubberts and Lambert James Mulder, citizens of the United States, residing respectively at 47 Packard Ave. S. E., Grand Rapids, in the county of Kent and State of Michigan, and 1416 Sherman Street S. E., Grand Rapids, in the county of Kent and State of Michigan, have invented a new, original, and ornamental Design for a Chair, of which the following is a specification, reference being had to the accompanying drawing, forming a part thereof, wherein—

Figure 1 is a front elevational view of the chair embodying our new design;

Figure 2 is a side elevational view of the chair, partly in section;

Figure 3 is a plan view of the chair;

Figure 4 is a perspective view of the chair;

Figure 5 is a cross sectional view showing the contour of a leg member taken on line 5—5 of Figure 4;

Figure 6 is an enlarged detail of the back of the chair;

Figure 7 is a side view thereof partly in section on line 7—7 of Fig. 6; and

Figure 8 is a plan view partly in section of the chair back taken approximately on line 8—8 of Figure 6;

We claim:

The ornamental design for a chair, substantially as shown.

JOHN J. LUBBERTS.
LAMBERT JAMES MULDER.
